UNITED STATES PATENT OFFICE

166,894

CONTAINER FOR COMESTIBLES

Ruby D. Whitney, Chicago, Ill.

Application January 15, 1952, Serial No. 18,062

Term of patent 14 years

(Cl. D58—2)

To all whom it may concern:

Be it known that I, Ruby D. Whitney, a citizen of the United States, and a resident of Chicago, in the county of Cook and State of Illinois, have invented a new, original, and ornamental Design for a Container for Comestibles, of which the following is a specification, reference being had to the accompanying drawing, forming part thereof.

Figure 4 is a perspective view, showing the container in a substantially closed position as when not in use; and

I claim:

The ornamental design for a container for comestibles, substantially as shown.

RUBY D. WHITNEY.
